UNITED STATES PATENT OFFICE.

MILO COVEL, OF CHICAGO, ILLINOIS.

SAW-SHARPENING MACHINE.

SPECIFICATION forming part of Letters Patent No. 319,794, dated June 9, 1885.

Application filed December 6, 1883. (No model.)

To all whom it may concern:

Be it known that I, MILO COVEL, of Chicago, county of Cook and State of Illinois, have invented certain new and useful Improvements in Saw-Sharpenering Machines, of which the following is a full, clear, and exact description, that will enable others to make and use the same, reference being had to the accompanying drawings, forming a part of this specification.

This invention relates to improvements in that class of saw-sharpening machines set forth in my Letters Patent No. 215,267, and Reissue No. 10,099.

The nature of this invention consists in the construction and arrangement of the mechanism for transmitting motion to the emery-wheel and feed-finger, and in means for adjustment relative to different-sized teeth, and also for clamping the saw in position during the operation of sharpening the same, as will be hereinafter more fully set forth in detail.

Figure 1 is a front elevation of a machine embodying my improved features, and Fig. 2 a detached detail; Fig. 3, a detached sectional detail. Fig. 4 is a side elevation.

Referring to the drawings, A represents the supporting frame-work, and A' A² two vertical shafts, and A³ a horizontal shaft, which are connected together by means of beveled gear-wheels, as shown, and put in motion by means of the hand-crank A⁴, for the purpose of raising and lowering the saw; but as this mechanism presents no new or novel features a detailed description will therefore be omitted.

The irregular-shaped cam B is mounted and rotates upon the front end of the shaft A⁵, and performs the dual functions of imparting the required reciprocating movement to both the emery-wheel B' and the feed-finger or push-pawl B². A beveled gear-wheel, A⁶, is mounted on the rear end of the shaft A⁵, which is adapted to engage with a companion gear-wheel, A⁷, placed at right angles thereto, and mounted on the shaft A⁸. The latter shaft has also mounted thereon the band-pulley A⁹, which receives and transmits the required motion from the motive power to the parts above described.

The outer end of the lever B³ is pivoted to

the bracket a, which is in turn attached to a part of the frame-work. To the inner end of this lever is attached the upper end of the connecting-rod B⁴ and the friction-roller a², placed a little back from the end of the rod B⁴, as shown in Fig. 1. This roller is adapted to have a rolling contact with the irregular cam B, for the purpose of imparting the required reciprocating movement to the lever B³.

The lower end of the connecting-rod B⁴ is attached to one end of the graduated arm C, the opposite end of said arm being pivoted to the supporting frame-work at a³. This arm is provided with a number of perforations, a⁴, arranged at regular intervals, for the purpose of adjusting the lower end of the connection with the emery-wheel gate to as many different positions as there are holes in the arm C. By shifting the lower end of the rod B⁴ from one hole to another in the arm C the emery-wheel is adjusted for different saws, in accordance with the required depth of the teeth. For instance, suppose hole No. 2 to be the adjustment for a tooth one-half of an inch in depth; No.

3, three-fourths of an inch in depth, and so on, each new position or distance between each hole representing one-fourth of an inch in the depth of the tooth. The holes in the arm C run from two to eight, in order to dress teeth from one-half inch to two inches, advancing one-fourth of an inch in regular order, all of the teeth being of the same shape, which is of course due to the irregular cam B, which imparts the same form to all the teeth alike, irrespective of the diameter of the saw or the depth of the teeth.

By this arrangement the adjustment is always exact and positive, which would not be the case were the arm C provided with a rectangular slot instead of the series of numbered apertures. A great deal of time is also saved where a number of saws of different sizes are dressed on the same machine, as the operator can see in a moment the precise adjustment or position of the rod B⁴ with relation to the arm C and the depth of the teeth.

The connecting-rod B⁴ consists of the sleeve b, the lower end of which slides loosely over the pin b', and the rod proper, the lower end of which is screw-threaded and engages with the correspondingly-threaded upper end of the sleeve, and is locked in any position it

may be adjusted to by the locking-nut b^2 . This arrangement readily permits of the rod being lengthened or shortened, as may be required. The lower end of the pin b' is bifurcated and straddles the arm C, as shown in Fig. 3 of the drawings. The upper end of the sleeve is enlarged, thus providing the shoulder b^3 , underneath which is coiled the lower end of the rod C', the upper end of the same being connected to the inner end of the hand-lever C². By depressing the outer end of the hand-lever C² the emery-wheel may be raised up from contact with the saw without stopping the machine, the sleeve sliding up on its loose joint connecting with the graduated arm C.

The upper end of the rod B⁵ is attached to the lug B' projecting from the rear side of the emery-wheel gate B⁶, as shown in Fig. 4, by which means the required up-and-down movement is imparted to the emery-wheel gate. The emery-wheel gate is supported in the guide-frame B⁸, and has a slightly inclined movement, as shown in Fig. 1, whereby the emery-wheel is brought in contact with the teeth of the saw in such a manner as to impart a fine, sharp point to the same. The required rotary motion is imparted to the emery-wheel and arbor, on which the same is mounted, by a belted connection with the band-pulley B⁹, mounted at the back part of the machine, as shown in Fig. 4.

One end of the rod D has a crank connection with the irregular cam B, which in this case performs the functions of a crank-wheel. The opposite end of this rod is connected to the lower end of the graduated arm D', the upper end of which is pivoted to a bracket projecting downward from the top of the frame-work, and is adapted to have a swinging movement. The arm D' is provided with apertures corresponding in arrangement and number with similar apertures in the arm C. One end of the companion rod D² is also connected to the arm D', and is adapted to be adjusted to as many different positions as there are holes in the arm. The opposite end of the rod D² is attached to the vertical lever D³ at a point near its longitudinal center. This lever is pivoted at the lower end to the frame-work, the upper end being adapted to move back and forth when the mechanism is in operation. The upper end of this rocking lever is provided with the feed-finger B², which is adapted to have contact with the teeth of the saw, and feed the same forward to the emery-wheel in regular order of succession. This feed-finger may be set so as to give the emery-wheel a light or heavy cut on the teeth by means of the right and left joint d' on the rod D².

d' is a rest for the feed-finger, and is adjustable to different positions by means of the elongated slot d'. This rest is for the purpose of adapting the feed-finger to different-spaced teeth, and the distance the same is to drop down between the teeth.

The shifting of the rod D² in the different holes in the arm D' is for the purpose of adjusting these parts in accordance with the distance the teeth are apart in the different saws. 70 One-half the distance between the points of the teeth is equal to the depth of the same, so that the connection with the two graduated arms may usually be arranged with reference to each other, in order to have a uniform operation. 75

E represents an eccentric clamping-lever pivoted to the under side of the top frame-piece, the head or end F being adapted to clamp the saw-plate just below the line of the 80 teeth for the purpose of stiffening and holding the saw in proper position relative to the emery-wheel during the operation of dressing the same. This lever is thrown into or released from a clamping position by means of 85 the handle F. By moving this handle in one direction the end F is brought into contact with the saw-plate, and by moving the same in the opposite direction the clamping end is thrown away from the saw. 90

Having thus described my invention, what I claim as new, and desire to secure by Letters Patent, is—

1. The combination, with the irregular-shaped cam-wheel B, of the lever B³, pivoted at one end, the opposite end being adapted to rise and fall, the friction-roller a², the rod B⁴, the graduated arm C, provided with a number of apertures arranged at regular intervals, and the adjustable connecting-rod B⁵, whereby motion is transmitted to the emery-wheel and the shape and depth of the teeth determined, substantially as described. 95 100

2. In a saw-sharpening machine, the combination, with an emery-wheel, of a moving gate supporting said wheel, a guide-frame, the loose sleeve b, having a loose joint at the lower end, and the shoulder b³ on the upper end, the rod C', and the hand-lever C², whereby the emery-wheel may be raised from contact with the saw without stopping the machine, substantially as set forth. 110

3. The combination, with the cam B, adapted to perform the functions of a crank-wheel, of the connecting-rod D, the graduated arm D', the adjustable companion rod D², the vertical lever D³, and the feed-finger B², whereby the required movement and adjustment are given to said feed-finger, substantially as described. 115 120

4. The combination, with the feed-finger B², of the adjustable rest d', provided with the elongated slot d', whereby said feed-finger may be adapted to conform to teeth of various shapes and depths, as set forth.

MILO COVEL.
